UNITED STATES PATENT OFFICE.

JOHN A. KELLY, OF BROOKLYN, NEW YORK, ASSIGNOR TO UNITED SHOE MACHINERY CORPORATION, OF PATERSON, NEW JERSEY, A CORPORATION OF NEW JERSEY.

HEEL-SEAT-FITTING MACHINE.

Application filed November 15, 1926. Serial No. 148,453.

This invention relates to machines for use in the manufacture of shoes and is illustrated as embodied in a heel-seat fitting machine arranged also to mold and smooth the counter portions of shoes during the performance of the heel-seat fitting operation. This application is a continuation in part of my copending application Serial No. 46,711, filed July 29, 1925.

In the manufacture of shoes to which wood heels are to be attached, it is usual to trim surplus stock from the heel-seat portions of their soles to cause the heel-seat portions of the shoes to fit the concave attaching surfaces of the heels in such a way that the edges of the heels may engage the shoe uppers closely adjacent to the edges of their soles so that the edges of the heel-seat portions of the soles are not visible in the finished shoes. As a part of this operation, a pair of shoulders are often formed at the heel-breast line of the sole against which the breast of the heel is positioned when the heel is attached. These shoulders serve as abutments to support the heel against forward displacement while it is being attached and to conceal any minor variation between the convex curvature of the forward portion of the heel-seat and the concave curvature of the corresponding portion of the heel. It is an object of the present invention to provide improved mechanism for cutting such heel-breast-receiving shoulders in the soles of shoes. As illustrated, these shoulders are cut by a pair of knives carried by fingers mounted upon a pivot substantially at right angles to the sole of the shoe operated upon and carried by an arm extending forward of the heel-breast line of its sole. Simple mechanism is provided to swing the knife-carrying fingers about their pivot so as to cause the knives to cut the heel-breast-receiving shoulders in the sole.

In order to improve the appearance of the shoes operated upon, a feature of the invention comprises the combination of means for cutting heel-breast-receiving shoulders or other abutments at or adjacent to the heel-breast lines of the soles of shoes with a mold arranged to contact with the counter portions of the uppers of the shoes during the

cutting of said shoulders or abutments to smooth the upper leather of the counter portions of the shoes and to eliminate any wrinkles that may be present.

With the above and other objects and features in view, the invention will now be described with reference to the accompanying drawings and pointed out in the claims.

In the drawings,

Fig. 1 is a perspective view of a portion of a heel-seat fitting machine embodying the present invention;

Fig. 2 is a perspective view, on a larger scale, of the shoulder-cutting and the counter-molding portions of the machine;

Fig. 3 is a cross-sectional view on the line III—III of Fig. 2; and

Fig. 4 illustrates the heel portion of a shoe after the completion of the heel-seat fitting and molding operation, showing also the chip detached from the sole in the heel-seat fitting operation.

The invention is illustrated herein as embodied in a heel-seat fitting machine of the type illustrated in an application for Letters Patent of the United States filed March 9, 1925, in the name of William C. Stewart and Harry L. Hood, and having Serial No. 14,137. Since the general organization of the machine may conveniently be as illustrated in said application, the drawings of this application disclose no more of that machine than is necessary for a full understanding of the present invention.

In accordance with the showing of said application, Serial No. 14,137, the illustrated machine is provided with a pair of crease plates 10 mounted in a table 12 for pivotal movement about a point 14 substantially in alignment with the back seam of the shoe to be operated upon, shown at 16, which is carried by a suitable work support 18 pivoted at 19 for movement into and out of operative relation to the crease plates 10. In accordance with a well-known practice in machines of this character, crease plates 10 are provided with thin edges 20 (best shown in Figs. 2 and 3) arranged to enter the rand crease of the shoe to be operated upon and to support the peripheral portion of the heel-seat of the sole of the shoe during the

heel-seat fitting operation. In accordance also with a usual practice in the construction of heel-seat fitting machines, appropriate means, which form no part of the present invention and are therefore not shown in the drawings, may be supplied, as illustrated, for example, in said application, Serial No. 14,137, for beveling the peripheral portion of the heel-seat of the sole of the shoe 16.

10 The crease plates 10 of the illustrated machine carry on their lower surface or are formed with mold members 22 shaped to apply pressure to the counter portion of the upper of the shoe operated upon, these mold members being moved with the crease plates about point 14 in alignment with the back seam of the shoe. To cause mold members 22 more effectively to shape the shoe upper to the last 23 upon which it is mounted and to remove any wrinkles which may be present, they are provided with electric resistance units 24 by which they may be heated. As illustrated, mold members 22 are hollow and resistance units 24 are housed therein.

15

20

25

Carried by the frame of the machine is an arm 26 projecting over the shank of the shoe upon the work support 18 forwardly of its heel-breast line. Carried by a pivot 28 mounted near the forward end of arm 26 are a pair of fingers 30, 32, each of which carries at its forward end a knife blade or cutter 34 arranged, when arms 30 and 32 are swung about pivot 28, to cut heel-breast-receiving shoulders 36 at the breast line of the sole of the shoe, as shown in Fig. 4. Preferably, and as illustrated in Fig. 2, the portions of the cutting edges of blades 34 toward the center line of the shoe are somewhat inclined so that the portions of the cuts nearer to the center line of the shoe do not extend through the full depth of the sole but become gradually shallower, finally emerging at the tread surface of the sole, as shown at 38 in Fig. 4. In order to swing fingers 30, 32 about pivot 28, each of those fingers is provided with a pin 40 positioned in one of a pair of slots 42 carried by a bar 44 mounted for sliding movement in ways formed in or carried by the frame of the machine, as shown at 45, Fig. 1. Suitable mechanism for moving bar 44 back and forth is provided comprising a treadle-operated rod 46 connected at its upper end to a bell crank lever 48 fulcrumed at 50 to the frame of the machine and connected by a link 52 with bar 44. Thus the depression of rod 46 moves bar 44 in a direction to swing knife blades 34 toward each other, cutting heel-breast-receiving shoulders 36 in the sole. To limit the movement of knife blades 34 toward each other and to prevent the cuts made by these knives from extending too far toward the center line of the sole, finger 30 is provided with a stop illustrated as an ad-

justable screw 54 arranged to impinge upon finger 32 at the end of the desired movement of knife blades 34.

In the operation of the machine, a shoe mounted upon a last is placed upon work support 18 and is moved rearwardly into engagement with crease plates 10 the thin edges 20 of which are caused to enter the rand crease of the shoe to support the edge of its sole. Mold members 22 thus engage the counter portion of the shoe upper and smooth out any wrinkles or other irregularities present. While the shoe is thus held, the peripheral portion of the heel-seat may be suitably beveled and heel-breast-receiving cuts are made by swinging fingers 30, 32 and cutters 34 about pivot 28, thus concluding the operation and removing a horseshoe-shaped chip, as indicated at 56, in Fig. 4.

Having described the invention, what I claim as new and desire to secure by Letters Patent of the United States is:—

1. A heel-seat fitting machine having, in combination, a pair of fingers mounted for pivotal movement about a point forward of the heel-breast line of a shoe to be operated on, a cutter carried by each finger, and means for swinging the fingers to cause the cutters to cut heel-breast-engaging shoulders in the sole of the shoe.

2. A heel-seat fitting machine having, in combination, a work support arranged to carry a shoe to be operated upon, an arm overhanging the shank portion of the sole of a shoe carried upon said support, a pair of fingers pivoted to said arm at a point above the shank of the shoe, a cutter carried by each finger, and means for swinging the fingers about the pivotal support to cause the cutters to form heel-breast-engaging shoulders upon the sole of the shoe.

3. A heel-seat fitting machine having a work support arranged to carry a shoe to be operated upon movable into and out of operative position, an arm overhanging the shank of a shoe carried by said support, a pair of fingers pivoted to said arm above the shank of the shoe, a knife carried by each finger, and means for swinging the fingers about the pivotal support to cause the knives to cut heel-breast-receiving shoulders in the sole of a shoe.

4. A heel-seat fitting machine having a work support arranged to carry a shoe to be operated upon, an arm extending forward of the heel-breast line of a shoe in operative position upon said support, a pair of fingers pivoted to said arm forward of the heel-breast line of the shoe, a knife carried by each finger, and means for swinging the fingers about the pivotal support to cause the knives to cut heel-breast-receiving shoulders in the sole of a shoe.

5. A heel-seat fitting machine having, in combination, a work support, a crease plate

arranged for engagement with the rand crease of a shoe upon the support, an arm overhanging the shank of a shoe upon the support with the crease plate engaging its rand crease, a finger pivoted to said arm forwardly of the heel-breast line of the shoe, a knife carried by said finger, and means for swinging the finger about its pivot to cause the knife to cut a heel-breast-receiving shoulder in the sole of a shoe.

6. A heel-seat fitting machine having, in combination, a work support a pair of relatively movable crease plates arranged for engagement with the rand crease of a shoe upon the support, an arm overhanging the shank of a shoe positioned upon the support with the crease plates engaged in its rand crease, a pair of fingers pivoted to said arm forwardly of the heel-breast line of the shoe, a knife carried by each finger, and means for swinging the fingers about their pivot to cause the knife to cut heel-breast-receiving shoulders in the sole of the shoe.

7. A heel-seat fitting machine having, in combination, a work support, a mold arranged to shape the counter portion of a shoe and to control the position of the shoe upon the support, a cutter, and means for operating said cutter to make a heel-breast-receiving abutment in the sole of the shoe while the shoe is engaged by the mold.

8. A heel-seat fitting machine having in combination, a work support arranged to carry a shoe to be operated upon, means for molding the counter portion of the shoe, and a cutter arranged to form a heel-breast-receiving cut in the sole of the shoe while the shoe is engaged by said molding means.

9. A heel-seat fitting machine having, in combination, a work support, a mold comprising a plurality of pivotally movable mold sections, and a cutter arranged to form a heel-breast-receiving abutment in the sole of a shoe mounted on said support while the shoe is engaged by the mold.

10. A heel-seat fitting machine having, in combination, a work support arranged to carry a shoe to be operated upon, a pair of crease plates mounted for pivotal movement about an axis substantially in line with the back seam of a shoe upon the support arranged to enter the rand crease and support the edge of the sole of the shoe, a mold section for molding the counter portion of the shoe carried by each crease plate, and a cutter arranged to form a heel-breast-receiving cut in the sole of a shoe while the shoe is engaged by said mold sections.

11. A heel-seat fitting machine having, in combination, a work support arranged to carry a shoe to be operated upon, a pair of crease plates pivotally movable about an axis substantially in line with the back seam of a shoe in operative position upon said support and having edges arranged to enter

the rand crease of the shoe, mold sections carried by said crease plates for molding the counter portion of the shoe, an arm overhanging the shank portion of the shoe upon the support, and a cutter carried by said arm operable upon the heel-seat portion of the sole of the shoe while the counter portion of the shoe is being shaped by said mold sections.

12. A heel-seat fitting machine having, in combination, a work support arranged to carry a shoe to be operated upon, a mold arranged to shape and engage the counter portion of a shoe upon said support, means for heating said mold, a cutter, and means for moving the cutter transversely of the heel-seat portion of the sole of the shoe while the counter portion of the shoe is being shaped by said mold to form a heel-breast-receiving abutment at the heel-breast line of the sole of the shoe.

13. A heel-seat fitting machine having, in combination, a work support arranged to carry a shoe to be operated upon, a mold arranged to engage and shape the counter portion of a shoe, means for heating said mold, a cutter, and means for moving said cutter to cause the cutter to form a heel-breast-receiving abutment at the heel-breast line of the sole of the shoe upon the support to prepare the sole for the reception of a wood heel.

14. A heel-seat fitting machine having, in combination, a work support arranged to carry a shoe to be operated upon, a mold comprising a pair of pivotally movable mold members arranged to engage and shape the counter portion of a shoe, means for heating said mold, a pair of cutters, and means for moving said cutters from the opposite edges of the sole of the shoe at the heel-breast line inwardly to form heel-breast-receiving shoulders in the sole.

15. A heel-seat fitting machine having, in combination, a work support arranged to carry a shoe to be operated upon, a pair of crease plates pivotally movable about an axis substantially in line with the back seam of a shoe in operative position upon said support and having thin edges arranged to enter the rand crease of the shoe, a mold carried by said crease plates for molding the counter portion of the shoe, an electric heater for said mold, and a cutter operable upon the heel-seat portion of the sole of the shoe while the counter portion of the shoe is being shaped by said mold sections to form a heel-breast-receiving abutment at the heel-breast line of the sole of the shoe.

16. A heel-seat fitting machine having, in combination, a support for a shoe to be operated upon, an arm overhanging the shank of a shoe upon the support, a finger carried by said arm and mounted for pivotal movement about a point forward of the heel-

breast line of the shoe upon the support, a cutter carried by said finger, and means for swinging the finger about its pivot to cause the cutter to cut a heel-breast engaging shoulder in the sole of the shoe.

17. A heel-seat fitting machine having, in combination, a pair of crease plates arranged to enter the rand crease of a shoe to position the shoe and support the edge of the heel-seat portion of its sole, an arm overhanging the shank of a shoe thus positioned, a finger

carried by said arm and mounted for pivotal movement about a point forward of the heel-breast line of the shoe, a cutter carried by said finger, and means for swinging the finger about its pivot to cause the cutter to cut a heel-breast engaging shoulder in the sole of the shoe. ¹⁵

In testimony whereof I have signed my name to this specification.

JOHN A. KELLY.
